[57] CLAIM

The ornamental design for a fruit peeler, as shown and
described.

DESCRIPTION

FIG. 1 is a front elevational view of a fruit peeler showing
our new design, the opposite side being a mirror
image;

FIG. 2 is a top plan view thereof;

FIG. 3 is a right side elevational view thereof;

FIG. 4 is a left side elevational view thereof; and

FIG. 5 is a bottom plan view thereof.

FIG. 1

FIG. 3

FIG. 2

FIG. 5

FIG. 4
